UNITED STATES PATENT OFFICE.

FRED M. DAVIS, OF CHICAGO, ILLINOIS, ASSIGNOR TO PULLMAN COUCH COMPANY, OF CHICAGO, ILLINOIS, A CORPORATION OF ILLINOIS.

SOFA-BED.

1,258,991.

Specification of Letters Patent. Patented Mar. 12, 1918.

Application filed May 3, 1915. Serial No. 25,477.

To all whom it may concern:

Be it known that I, FRED M. DAVIS, a citizen of the United States of America, and a resident of Chicago, county of Cook, and 5 State of Illinois, have invented certain new and useful Improvements in Sofa-Beds, of which the following is a specification.

The main objects of this invention are to provide an improved form of sofa bed in 10 which the device may be converted from sofa to bed form and vice versa by substantially one movement or operation; to provide such a device in which the movable parts are compact when folded and are 15 easily demountable from the frame, and in which the sofa frame may be of substantially the same style and shape as usual in sofa beds; to provide an improved form of bed bottom in which the outermost or foot 20 section in its sofa position is disposed uprightly behind the seat and sofa back proper, and has legs arranged for automatic operation; to provide an improved form of arms for swinging the foot or back section 25 and for supporting it in its sofa and bed positions; to provide in a sofa bed a foldable bed bottom in which an intermediate section is secured to the under side of the seat frame, and the combined seat frame and 30 bed section are overturnable by a somersaulting action to a forward position; to provide an automatically operable cover on the frame back for concealing the top of the foot section and folded legs when swung 35 to sofa position; to provide improved means for controlling the legs and back cover respectively; and to provide improved automatic means for supporting the head section and adjacent section in bed position, 40 and for releasing the bed bottom to fold when the foot section is raised.

Two illustrative embodiments of this invention are shown in the accompanying drawings, in which:

45 Fig. 1 is a side view of a sofa bed in its sofa form with the near end of the sofa frame removed.

Fig. 2 is a similar view with the device in its bed form.

50 Fig. 3 is an enlarged view of a support bearing for the rear part of the head section, in sofa position.

Fig. 4 is an enlarged fragmentary top

view of the pivotal mounting for the foot section arms and swinging front panel.

55

Fig. 5 is a fragmentary cross section on the line A—A of Fig. 2.

Fig. 6 is an end view of the foot section and back in their bed position with the legs extended.

60

Fig. 7 is a top view of the foot section and back in their sofa position with the legs retracted.

65

Fig. 8 is an enlarged fragmentary section on the line B—B of Fig. 2.

Fig. 9 is an enlarged fragmentary section on the line C—C of Fig. 2.

70

Fig. 10 is an enlarged perspective view of the guide means on one side of the seat frame.

75

Fig. 11 is a side view of a modified form of bed bottom in its folded position.

Fig. 12 is a view of the under side of the foot section and of the adjacent part of the seat section of the modified form in their bed position.

Fig. 13 is an end view of the foot section of the modified form in its bed position with the legs extended.

80

Fig. 14 is an enlarged cross section on the line D—D of Figs. 11 and 12.

85

Fig. 15 is an enlarged cross section on the line E—E of Figs. 11 and 12.

Fig. 16 is an enlarged cross section on the line F—F of Figs. 12 and 13.

90

Fig. 17 is an enlarged fragmentary view of the joint connecting two of the links adjacent to the supporting arm on the foot section.

In the construction shown in Figs. 1 to 10, the sofa bed comprises a frame 1 having ends 2 and cross members 3, a foldable sectional bed bottom 4, a seat 5, a back 6, and a swinging top or cover 7.

The bed bottom includes mainly a foot or back section 11, a seat section 12, a short connecting section 13, and a bottom section 14, and preferably a fifth or head section 15 is also provided.

95

The back section 11 is provided with arms 17 projecting forwardly and downwardly and supported turnably adjacent to the lower front part of the frame for swinging said section forwardly and downwardly to its bed position. The lower ends of the arms 100 17 may be held in any turnable manner, but

105

may to advantage rest demountably in open topped sockets 19 on the frame ends, and the arms may have pivot shoulders 21 to rest in said sockets. Said arms are curved or 5 angular and in their bed position support the adjacent parts of the seat and back sections directly from the floor, as shown in Fig. 2.

The back 6 is movable with respect to the 10 frame 1, and is preferably carried by the foot section 11, in movable relation thereto as hereinafter described.

The seat 5 is mounted for overturning in 15 converting the device from one form to the other. Its rear part is attached to the seat section 12, and its front part is supported on the front part of the frame 1. The seat is provided with horizontal lateral guides 23, and the frame has shoulders or pivot 20 like studs 24 to engage said guides for supporting the forward part slidably as the seat is turned through a somersaulting motion in swinging to and from its inverted or bed position.

25 The seat section is preferably shorter than the depth of the seat proper, but these relative dimensions may be varied widely according to particular requirements in different cases.

30 The head section 15 is mounted turnably with relation to the frame, adjacent to its rear edge, as on pivots 26, one on each side. When such a fifth or head section is used, it serves also as means for raising the rear 35 part of the bottom section 14 to its bed position.

Rule joints, or the equivalents, are preferably provided at both ends of the short section 13, though when arranged precisely 40 as in Fig. 2, the joints may all be free. As the back section 11 swings into bed position it pulls the rearward sections up into alignment. This lifting of the intermediate sections is made further effective by having 45 the pivots 26 offset upward from section 15 as by a bracket 29.

Coacting support means are provided on the frame and bed bottom, to secure the adjacent parts of the head and bottom sections 50 15 and 14 in raised position. A guide or stop 31 on each frame end 2, and a shoulder 32 on each side of the head section answer this purpose.

Each pivot 26 is preferably carried 55 demountably in a lateral frame-supported bearing member 35 having an open topped socket 36. Said member 35 is preferably slidable horizontally somewhat, as on a guide 37, and provided with retracting 60 means, as for instance a spring 38 connected to the support 35 at 39 and to the frame end 2 at 40. Support 35 is held by means 43 reciprocatable in slots 44 in the guide 37. Said spring urges the sections 65 rearward, and when the foot section is raised

draws back the section shoulder 32 out of registry with the support 31 and so permits the device to fold. The tension of said spring helps lift the foot section in folding. In unfolding, the spring 38 holds back the 70 shoulder 32 until it is raised above the level of support 31, and then said shoulder is drawn forward onto support 31 by the final lowering movement of the back section overcoming the tension of spring 38. In bed position the connecting section 13 is supported 75 horizontally by the rearward part of the seat.

The back 6 is attached to the foot section 11 in such manner as to swing downward 80 somewhat therefrom in its bed position, enough to give ample clearance for the usual woven-wire bed spring, and also so as to operate certain legs as hereinafter described. For this purpose links 48 are provided at 85 opposite edges of the back, each of said links being turnably connected at its end to the back and foot section respectively. Preferably one end of each link is pivoted to the upper part of the back, and the opposite end to the lower or inner part of the foot section. A bracket 50 may to advantage be provided on the foot section 11 for supporting the lower pivot 51 of said link spaced forward somewhat from said section. 90 By this arrangement the relative longitudinal movement of the back and foot section in swinging is reduced to a minimum. The outward or divergent swing of the back, with respect to the foot section, is limited 95 by suitable means, as for instance a flexible strap 53 at the lower edge of the back, and a plate 54 at the upper edge of the back as hereinafter more fully described.

Foldable legs 57 are provided on or adjacent to the outer end of the foot section 11. Said legs are preferably attached to the foot rail 58 as by the pivots 59 shown in Fig. 6. Automatic means are provided for extending and retracting said legs as the 110 foot section is swung to its bed and sofa positions respectively. For this purpose the movement of the back with relation to the foot section is utilized. The upper means 54 for limiting the divergent swing of the 115 back from the foot rail may be formed and arranged to control the legs, and for this purpose said means 54 is preferably made in the form of a plate. Said plate has slots 61 for guiding studs 62 carried by the angled 120 upper ends of the legs as on the short arms 63, and also slots 65 coacting with studs or shoulders 67 on the foot rail. The leg controlling slots are disposed longitudinally, and the slots for the foot rail studs are 125 disposed transversely of the plate. The plate 54 is preferably connected turnably to the back, as by hinges 69 so as to provide for more or less movement of the back longitudinally of the bed bottom such as re- 130

sults from the swinging arrangement of the back above described. The legs are formed to overlap, one with respect to the other, in folding, so as to lie compactly against the 5 guide plate 54, opposite the foot rail 58 when the foot section is swung to its sofa position.

Automatic means are provided for controlling the cover 7 which normally 10 encloses the top of the foot section and legs 57. For this purpose the cover is mounted swingably as on pivots 71, adjacent to its rear edge upon the frame ends 2, and is urged to its closed position by yielding 15 means 72, a seat or stop member 73 being provided to determine its closed position, particularly when the bed is unfolded. Projecting cam means 75 are provided on the 20 foot section adjacent to its outer edge, as for instance, a pair of cam plates one on each side of the foot section. Said cam plates are formed to project backward somewhat from the top of the foot section, as shown in Fig. 1, and project beyond the end 25 of said section sufficiently to throw the cover 7 upwardly enough to clear the legs 57, the rearward tip of each plate being disposed low enough to pass under the forward edge of said cover, so as to throw the latter upward.

Stop means 77 are provided one on each 30 frame end 2 for arresting the rearward swing of the foot section in folding the device. A handle or strap 78 is provided on the upper part of the foot section, whereby the latter may be pulled forward and downward to its sofa position.

A movable panel 80 is provided for the 40 lower front part of the sofa frame, said panel being turnably mounted adjacent to its lower edge, and being swingable forwardly to give clearance for the overturning of the seat 5. Said panel is preferably carried by substantially the same pivot 45 means as the arms 17. In order that said panel may assist in holding the frame ends in fixed spaced relation, the pivot means on the lower end of arm 17 is provided with a head 82, and the socket 19 therefor is 50 flanged to secure the pivot against longitudinal movement. Said panel is provided with a bracket 81 carried by an inward pivot projection 83 on said arm 17, and is secured in place by suitable means, as a pintle 84. 55 The headed pin 24 and flanged guide 23 on the seat assist with said panel to hold the ends 2 in spaced relation. Said panel at its upper edge rests against the front of the seat frame, and is preferably beveled so as 60 to be swingable forward by the turning action of said seat against the tension of the spring 86 which urges said panel to its upright position through the medium of lever arm 87. Said panel is swung forward further by the adjacent part of arm 17, as

shown in Fig. 2, though the initial movement is usually caused by coaction with the front edge of the seat.

The sofa bed is assembled as follows: The frame ends 2 are connected by the cross-members 3. The bed bottom, back and seat members are then connected together and inserted into the frame, the arm pivot 21 being dropped into its socket 19, the seat held in position substantially as shown in 75 Fig. 1, being slid into engagement with the shoulders 24 on the frame ends, said shoulders entering the open ends of guides 23, and the pivots 26 of the head section being dropped into their sockets in the guides 35. 80 The device may be taken apart or knocked down by a reverse operation.

The operation for unfolding the device is as follows: The operator grasps the handle 85 78 and swings the foot section to its bed position by a single movement, thereby causing the seat to overturn by a somersaulting action, the back to swing down and unfold the forward legs, and the bed sections to swing into alignment in their rigidly supported bed position.

In folding the device, the operation is as follows: The operator grasps the handle 78, or the free end of the foot section and swings the same upwardly and backwardly 95 to its sofa position, thereby causing the bed sections to assume their position as shown in Fig. 1 with the mattress and bedding in made-up form, as will be understood. Gravity swings the back 6 against the foot section 11 and thereby folds legs 57. This restoring action may be assisted or hastened by a push with the hand.

In the construction shown in Figs. 11 to 17 the legs 90 for the foot section 91 are 105 operated by connections leading therefrom to the seat section 92, whereby relative turning of the foot and seat sections effects a corresponding definite swinging of the legs.

The seat section 92 has rearwardly projecting arms 93, and the foot section has links 94 disposed longitudinally of its side rails. Links 95 are turnably connected at their opposite ends to the outer ends of said arms 93 and to the adjacent ends of the links 94 115 through the medium of a connector 96. Each leg 90 is turnably connected to the outer part of the foot section and is foldable to a concealed position back of the flange of the foot rail when the bed bottom is folded. 120 Means are provided connecting said legs and said links 94 comprising links 97 disposed longitudinally of the foot rail, diagonal links 98 to connect said links 94 and 97, and links 99 connecting the legs 90 and links 125 97. In order to effect the proper operation of the legs each leg 90 is controlled by the arm 93 on the opposite side of the foot section, the links 97 being crossed to transmit motion from one side of the bed to the other. 130

In this instance the frame members of the bed bottom are arranged with their vertical flanges disposed downwardly in bed position, so as to facilitate hiding the legs 5 90 behind the vertical flange 100 of the foot section, the position of the legs when folded being shown by dotted lines in Fig. 16. The horizontal flanges of the foot section frame members are slotted longitudinally 10 in an appropriate manner to provide for reciprocation of the several links and connecting pivots, as will be apparent from Figs. 11 to 16. Referring to Fig. 11, the arm 103 for the foot section is formed for 15 pivotal mounting at its lower end as at 104, and is bent oppositely from arm 17 of Fig. 1, whereby in its bed position it is disposed adjacent to, and over and back of, the seat supporting shoulder 24. The rear end of 20 the head section is adapted for pivotal support at 106. The links 95 and 96 are joined as shown in Fig. 17, link 96 being provided with a shoulder or bracket 108 to carry the joint pivot 109.

25 Although but two specific embodiments of this invention are herein shown, it is to be understood that no attempt has been made to show specifically all useful embodiments, and that numerous details of the 30 constructions shown may be altered or omitted without departing from the spirit of this invention, as defined by the following claims.

I claim:

35 1. A device of the class described, comprising a frame, and movable seat and back members, in combination with a foldable bed bottom including a back section, a seat section, a connecting section, a bottom section, and a head section arranged in the order enumerated, said sections being foldable to provide a space for bedding in place on said bed bottom, said back section having an arm whereon it may be swung forward 45 from its upright normal position to its bed position about an axis in the lower front part of said frame, and said head section being turnably mounted adjacent to its rear edge on said frame.

50 2. A device of the class described, comprising a frame, and movable seat and back members, in combination with a foldable bed bottom including a back section, a seat section, a connecting section, a bottom section, and a head section arranged in the order enumerated, said sections being foldable to provide a space for bedding in place on said bed bottom, said back section being disposed normally behind said back member 55 and having an arm whereon it may be swung forward to its bed position, said seat section being secured to the reverse side of said seat member and being overturnable therewith, said seat member having sliding 60 and turning relation to said frame, and said

head section being swingably mounted adjacent to its rear end to said frame.

3. In a device of the class described, a frame, in combination with a foldable bed bottom including a back section and a seat 70 section, said back section having an arm whereon it is swingable from its back position to its sofa position and reversely, a back member disposed normally in front of and adjacent to said back section and being 75 mounted to permit of swinging said back section forward, and a seat member having its rear part attached to said seat section, said seat member and frame at their front parts being formed to coact slidably for 80 forward and downward movement of said seat member in overturning to its sofa position.

4. In a sofa bed, a frame, a foldable sectional bed bottom mounted operatively 85 thereon and a back mounted in variable spaced relation on one of the bed bottom sections for control by gravity, a member attached to the back and having restricted coaction with said section to serve as stop 90 means for limiting the divergence of said section and back when the device is unfolded, and legs turnably connected directly to said section for directly supporting the bed bottom, said legs and member being 95 provided with coacting shoulder and guide means adapted to project and retract said legs as the back moves when the device unfolds and folds respectively.

5. A convertible seating device comprising 100 a turnably mounted bed bottom member disposed normally in upright position and being swingable to horizontal position, a back mounted on said member in movable relation thereto in a direction nearly perpendicular to the plane of said member, a leg pivoted to said member and foldable with respect thereto, leg controlling means attached to said back and overlapping the adjacent edge of said member, said means 110 and leg having coacting guide-cam and shoulder means formed and arranged to project and retract said leg by the divergent movement of the back and vice versa with respect to said member as said member 115 swings to and from its horizontal or bed position.

6. In a device of the class described, a frame, a swingably mounted bed bottom member having a normally upright position, 120 a back member carried on the front side thereof in movable relation thereto, and being movable downward by gravity away therefrom to a limited extent, legs mounted turnably on said bottom member for folding, means connecting said back member and legs for automatic control of said legs by the relative movement of said back and bottom members, said legs each having a part of its upper end offset and provided 130

with a shoulder, and said means including a plate hinged to said back member and overlying the end of said bed bottom member, said plate having slots for coaction 5 with the said shoulders on said legs, and means for limiting the divergent movement of said back and bottom members.

7. A convertible seating device, comprising a frame, a foldable sectional bed bottom, an overturning seat arranged to swing forward under the bed bottom, said bed bottom including an outer section having arms turnably connected to the lower front part 10 of said frame whereby said section is swingable from an upright position in the back of said frame to a horizontal position wholly in front of and spaced from said frame, an inner section turnably connected to the back part of said frame, and a plurality of 15 medial sections disposed normally under the seat and one of which is disposed adjacent to and is co-turnable with the seat.

8. A device of the class described, comprising a sofa frame, a movable back and 20 movable seat, in combination with a foldable bed bottom including a foot section, a head section, a middle section, a seat section, and another section adjacent to the head section, a supporting arm attached to said 25 foot section and having turning relation to and being supported by the lower forward part of said frame, the said seat section being adjacent to the foot section and being attached to the under side of the 30 seat, said head section being supported turnably adjacent to its rear edge on said frame, said sofa frame and seat having slidably related supporting means having a 35 point of coaction adjacent the front edge of 40 the sofa frame whereby said seat is overturnable by the forward movement of the foot section in unfolding the device.

9. A sofa bed, comprising a frame and a seat overturnably mounted for swinging forward to its bed position, in combination with a foldable sectional bed bottom having a section secured to the under side of said seat, a pivotal support adjacent to the front of said frame, guide means coacting with 45 said support on the side of said seat, and an arm connected turnably at one end to the lower front part of said frame and at its opposite end turnably to the rear part of said section as it appears in its sofa position.

10. A sofa bed, comprising a frame, and a seat overturnably mounted for swinging forward to its bed position, in combination with a foldable sectional bed bottom having 50 a section secured to the under side of said seat, a pivotal support adjacent to the front of said frame, guide means coacting with said support on the side of said seat, and an arm connected turnably at one end to the 55 lower front part of said frame and at its

opposite end turnably to the rear part of said section as it appears in its sofa position, said arm being angular to extend above and in front of said support in its sofa position.

70

11. A sofa bed, comprising a frame, and a seat overturnably mounted for swinging forward to its bed position, in combination with a foldable sectional bed bottom having a section secured to the under side of said seat, a pivotal support adjacent to the front of said frame, guide means coacting with said support on the side of said seat, and an arm connected turnably at one end to the lower front part of said frame and at its opposite end turnably to the rear part of said section as it appears in its sofa position, said arm being angular and arranged to bear upon the floor intermediately of its ends in its bed position.

85

12. A sofa bed, comprising a frame, and a seat overturnably mounted for swinging forward to its bed position, in combination with a foldable sectional bed bottom having a section secured to the under side of said seat, a pivotal support adjacent to the front of said frame, guide means coacting with said support on the side of said seat, and an arm connected turnably at one end to the lower front part of said frame and at its opposite end turnably to the rear part of said section as it appears in its sofa position, said arm in one of its positions being disposed at a distance from said support, and in another of its positions being disposed adjacent to said support and being curved to reach around said support.

90

13. A sofa bed comprising a frame having an inwardly projecting shoulder on its front part, a seat having a lateral guide to 105 coact with said shoulder, an arm turnably connected at its ends with the lower front part of said frame and with the rear part of said seat respectively, a front panel swingably mounted adjacent to its lower edge at 110 the lower front part of said frame, said panel being disposed in front of said arm and swingable forwardly and downwardly in converting the device to its sofa form, said arm being bent to extend around said 115 shoulder in one of its positions.

14. A sofa bed having a frame, in combination with a bed bottom including a series of foldably related sections comprising a seat section, a back section pivoted to 120 said seat section, a bottom section, and a connecting section pivoted at its opposite edges to said seat section and bottom section respectively, means attached to said back section and extending downward and 125 forward in turning relation to said frame for swinging said back section to its bed position, seat and back members each movable to a retracted or bed position, the seat member having its rear part attached to 130

- 5 said seat section and having its front part mounted in slot and shoulder relation to the adjacent parts of said frame for somersaulting action as the back section is swung forward, said bottom section being disposed normally substantially horizontally beneath the seat section in spaced relation thereto, and means for raising the rearward part of said bottom section as said back section is 10 swung to its bed position.

15 15. A sofa bed having a frame, in combination with a bed bottom including a series of foldably related sections comprising a seat section, a back section pivoted to said seat section, a bottom section, and a connecting section pivoted at its opposite edges to said seat section and bottom section respectively, means attached to said back section and extending downward and forward 20 in turning relation to said frame for swinging said back section to its bed position, seat and back members each movable to a retracted or bed position, the seat member having its rear part attached to said seat section and having its front part mounted in slot and shoulder relation to the adjacent parts of said frame for somersaulting action as the back section is swung forward, said bottom section being disposed normally substantially horizontally beneath the seat section in spaced relation thereto, and means for raising the rearward part of said bottom section as said back section is swung to its bed position, said back member being mounted upon said back section, the seat member being disposed substantially in alignment therewith under the bed bottom when the latter is unfolded.

25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900

16. A sofa bed having a frame, in combination with a foldable sectional bed bottom, the sections of which when folded form a storage receptacle adapted to hold the bedding in made-up form on the bed bottom, two adjacent sections at one end being back and seat sections respectively, means connecting the seat section to said frame in turning and sliding relation thereto, and the back section having arms projecting downwardly and forwardly in turnable relation to said frame for swinging said back section forwardly and downwardly to its bed position.

17. A sofa bed having a frame, in combination with a foldable sectional bed bottom, the sections of which when folded form a storage receptacle adapted to hold the bedding in made-up form on the bed bottom, two adjacent sections at one end being back and seat sections respectively, and the back section having arms projecting downwardly and forwardly in turnable relation to said frame for swinging said back section forwardly and downwardly to its bed position, said frame having inwardly projecting means on its front part and a seat member

attached to said seat section and having slots on its sides, said means normally coacting with said slots adjacent to the front of said seat member.

18. A sofa bed comprising a frame, in combination with a foldable sectional bed bottom including a back section having arms projecting forwardly and downwardly in turnable relation to the frame for swinging said back section to its bed position, and a plurality of sections swingable into bed position rearwardly of said foot section in its bed position, the rearmost section being supported for turning with respect to said frame and being movable longitudinally in its bed position, yielding means urging said head section horizontally, and means for supporting the forward part of the rear section and adjacent section in bed position, the mutual release and engagement of said means being controlled by said yielding means.

19. In a device of the class described, a sofa frame having ends, in combination with a foldable sectional bed bottom disposed operatively between said ends, a bearing member slideable forward and backward on one of said ends and having an open topped socket, the rearmost of said sections having on its rear part a projecting pivot resting in said socket, and on its forward part a projection, said sofa end having a shoulder with which said projection registers at times for support, and yielding means attached to said frame adapted and arranged to urge said bearing member horizontally to control at times the position of said shoulder with respect to said projection.

20. In a device of the class described, a frame, in combination with a foldable bed bottom comprising a seat section, a seat attached to said section, coacting pivot and slot means on the front part of said frame and seat respectively, and arms turnably connected at their ends to the lower front part of said frame and to the rear part of said seat section respectively.

21. A convertible seating device comprising a frame and a combined seat and bed bottom member, the one being slideable and turnable on the other, the former having pivots one on each side and the latter having slots extending backward on its sides, said slots being open ended at or adjacent to their front ends to receive said pivots respectively, arms turnably connected at their ends to the lower front part of said frame and to the rear part of said member respectively, and means limiting the forward and backward movement of said member.

22. A sofa bed comprising a frame, in combination with a foldable sectional bed bottom including a swinging outer section having forwardly projecting arms turnably supported adjacent to the lower front part of

- said frame for swinging said section forwardly to its bed position, legs folded across the outer or upper end of said section, a self closing cover mounted turnably adjacent to 5 its rear edge on the upper part of said frame and inclosing the adjacent end of said section and the legs thereon, and cam means on said section for raising the front part of said cover to admit said adjacent end of the 10 legs thereon as said section swings to its sofa position, said cam means comprising a pair of outwardly and rearwardly projecting plates attached to said section, and said back and cam means being freely swingable 15 forward from under said cover, and handle or pull means to facilitate manual swinging of said section.
23. In a device of the class described, a back member and a bed section member disposed normally in substantially upright position behind said back member, and being swingable to a horizontal position, links disposed uprightly and having their upper ends connected turnably to said back member and 25 having their lower ends connected turnably to said section member whereby said back member is carried swingably upon said section member, and means for limiting the divergent swinging of said back member.
24. In a sofa bed, a seat, in combination with means for supporting the front part thereof turnably and slidably, and means swingable about an axis below the front part of said seat for supporting the back part 30 thereof and for swinging the seat forward to an inverted position.
25. In a sofa bed, a frame, a seat supported turnably and slidably adjacent to its front edge on said frame, means pivotally 35 supported on said frame for swinging the rear part of said seat upward and forward to an inverted position in front of said frame, and a series of bed sections carried by said frame and said seat and movable 40 into alinement in a plane above said seat by the swinging of said seat.
26. In a sofa bed, an overturning seat supported turnably and slidably adjacent to its front edge, means for supporting the 45 rear part of said seat as it swings upward and forward to an inverted position, and a series of bed sections movable into alinement in a plane above said seat by the swinging of said seat, one of said sections being 50 attached to the under side of said seat and said sections being foldable to form a clothes receptacle under the seat.
27. A convertible seating device, comprising a frame and movable seat and back 55 members, in combination with a foldable bed bottom adapted to carry the bedding in made-up form when folded and including
- a back section, a seat section, a connecting section, and a bottom section, and a pair of arms for said back section whereon it may 60 be swung forward to its bed position and vice versa, said seat being swingable forward under the bed bottom when the device is unfolded, and said back section being disposed normally in upright position behind 65 said back member.
28. A sofa bed having a frame, in combination with a transversely extensible foldable bed bottom including a foot section and a head section mounted turnably on the 70 front and rear parts of said frame respectively, and a plurality of intermediate sections, one of said intermediate sections having a forwardly overturning seat member attached thereto for swinging therewith, said frame and seat member having a guide and pivot connection whereby the front part of said seat member is supported slidably and turnably on the front part of said frame.
29. In combination with a fixed frame, a 75 folding frame comprising five sections, the first or innermost section pivoted to the fixed frame at the rear at substantially bed height; the fifth or outermost section fulcrumed on the fixed frame at the forward 80 side near the floor level and having its outer end portion horizontal at extended position, the second section being pivoted to the free end of the first, the fourth pivoted to the horizontal portion of the outermost section, 85 the middle section being pivoted at its opposite ends to the proximate ends of the second and fourth sections, the joint between the second and third sections being at the extended position of the bed frame located 90 substantially vertically above the fulcrum of the outermost section to the fixed frame.
30. In a folding bed lounge, in combination with a fixed seat frame, a folding bed frame comprising five sections, the first three 95 joints being constructed for folding only in the direction which would cause them to move downward from the horizontally-extended position of the frame, the fourth joint being adapted also to fold in the opposite direction, supports on the fixed frame upholding the first and second joints at the horizontally-extended position of the frame, the first section having limited longitudinal movement at its pivotal connection with the fixed frame, the fifth section being fulcrumed on the lower part of the forward 100 side of said fixed frame.
- Signed at Chicago this 1st day of May 1915.
